UNITED STATES PATENT OFFICE.

ANDREW WEIMAR, OF PHILADELPHIA, PENNSYLVANIA, ASSIGNOR
OF ONE-HALF TO WILLIAM D. WEIMAR, OF PHILADELPHIA,
PENNSYLVANIA.

HEDDLE MECHANISM FOR LOOMS.

SPECIFICATION forming part of Letters Patent No. 793,025, dated June 20, 1905.

Application filed October 1, 1901. Serial No. 77,239.

To all whom it may concern:

Be it known that I, ANDREW WEIMAR, a citizen of the United States, residing in Philadelphia, Pennsylvania, have invented certain Improvements in Heddle Mechanism for Looms, of which the following is a specification.

My invention consists of a substitute for the cams and treadles sometimes used at the lower portion of a loom for operating the heddles thereof, the object of my invention being to increase the patterning capacity of such heddle-operating mechanism, to provide for readily changing from one pattern to another, and to so locate the mechanism that it will be over-head and out of the way of the weaver, but more readily accessible than cams at the bottom of the loom.

In the accompanying drawings, Figure 1 is a front elevation of sufficient of a loom to illustrate my invention. Fig. 2 is a front view of the same looking in the direction of the arrow α , Fig. 1. Fig. 3 is a plan view with the connections between the levers omitted in order to avoid confusion. Fig. 4 is a side elevation illustrating the spring connections for the lower ends of the heddles. Fig. 5 is a side view of part of the pattern-chain on a larger scale than the other figures, and Figs. 6, 7, 8, 9, and 10 are views of the different links comprising the chain.

In Fig. 1 of the drawings, 1 represents part of the fixed frame of the loom, and 2 the top arches of the same, these arches carrying bearings for transverse shafts 3, upon which are hung bell-crank levers 4, which are disposed in connected pairs or series and carry, by links and straps or other suitable connections 5, the heddles 6, these heddles being subjected to a constant downward pull by the action of springs 7, carried by frames 9, secured to the floor and acting upon levers 10, which are connected by straps 11 or equivalent devices to the lower portions of heddles, as shown in Fig. 4.

The upper portion of the loom-frame 1 has brackets 12, carrying a transverse shaft 13, onto which is slipped the slotted hubs of a series of levers 14 and 37, said hubs being retained in position upon the rod or shaft 13 by

means of a retaining-bar 15, mounted on the brackets 12 and bearing upon the outer portions of the hubs of the levers, as shown in Fig. 1. On withdrawing this bar, therefore, any one of the levers can be readily removed. The inwardly-projecting arm of each lever 14 carries an antifriction-roller 16, which bears upon a pattern-chain 17, mounted upon a drum 19, which is secured to and rotates with a shaft 20, the latter turning in suitable bearings on the frame 1 of the loom and having at one end a spur-wheel 21, which meshes with a spur-wheel 22 on a shaft 23, also mounted in suitable bearings on the fixed frame, said spur-wheel 22 being secured to or forming part of a bevel-wheel 24, which meshes with a bevel-pinion 25 at the upper end of a vertical shaft 26, the latter being rotated either continuously or by a series of intermittent movements from any available driving-shaft of the loom.

There are as many of the pattern-chains 17 as there are levers 14 employed in the loom, and each pattern-chain is composed of low links and high links, said high links being either single, as shown at the lower portion 75 of the chain in Fig. 1, or grouped and overlapping, as shown at the left-hand side of said chain, depending upon whether the projecting arm of the lever 14 is to be held in an elevated position for one or more links of the 80 chain, the disposition of the links of course depending upon the character of the pattern to be produced.

The upwardly-projecting arm of each lever 14 is notched for the reception of a loop-and-strap or equivalent connection 27 between said lever 14 and one of the levers 4, and each arm of each lever 14 is guided in a suitable grid, that for guiding the upper arms of the levers being represented at 29 and that for 90 guiding the inwardly-projecting arms of the levers being shown at 30 in Fig. 1. The upper grid 29 has a transverse shaft 31, upon which are hung a series of fingers 32, which can be thrown backward, as shown in Fig. 1, 95 or can be swung forwardly, so as to engage with notches 33 at the upper ends of the upwardly-projecting arms of the levers 14 in or-

der to hold the latter out of action when desired.

By the mechanism described the movement of the heddles is effected by the action of the 5 pattern-chain itself, the device in this respect being distinct from that class of heddle mechanisms in which the pattern-chain simply operates upon a jack so as to move the same into or out of engagement with a separate 10 heddle-operating mechanism. The use of the pattern-chain permits of a much greater variety of patterns than could be produced if the heddles were acted upon by cams on a cam-shaft, and patterns can be readily changed 15 by rearranging the links of the chains.

Upon a shaft carried by brackets 34 at the end of the loom I mount a drum 35, over which the pattern-chain can be looped when said chain is of considerable length, thereby preventing 20 said chain from hanging down so far as to interfere with the operation of any other part of the loom.

I find it advisable to provide the loom with means, in addition to those above described, for 25 operating a series of heddles—say four—for producing a plain weave, so that the chain-operated heddles may be used simply for the production of fancy weaves. For this reason I mount upon the front end of the shaft 20 a 30 series of cams 36, which have alternating high and low portions, these cams acting upon the series of levers 37; but these levers 37, instead of being connected directly to the levers 4, are connected by link-and-strap or 35 other connections 43 to arms 39 on rock-shafts 40, mounted in bearings in brackets 41, said rock-shafts 40 having other arms 42, which are connected to the levers 4 by link-and-strap or other connections 44. When 40 only a plain weave is desired, therefore, all of the levers 14 will be put out of action and the heddles operated solely by the cams 36. In the present instance I have shown the arms 42 as supplanting certain levers 14; but it 45 will be evident that the entire series of levers 14 may be used, and the arms 42 may be arranged laterally outside of the limits of said levers 14.

The special forms of links used in making 50 my improved pattern-chain are shown in Figs. 5 to 10. Each of the links has a tongue at its forward end for fitting a recess in the rear end of the preceding link and a recess at the rear end for receiving the tongue of the following link, the links being connected by transverse pins in the usual manner. The low link is shown at Fig. 6, the single lift-link at Fig. 7, and the group-links at Figs. 8, 55 9, and 10. The single lift-link has a rise 50, a dwell 51, and a drop 52, the rise and drop each extending throughout about one-half as many degrees of an arc as the dwell. The foremost of the group-links, Fig. 8, has a rise 53 and a dwell 54, which is extended in the 60 form of a rearwardly-projecting tail 55, the re-

cess of the link extending up through this tail portion of the same. The intermediate group-link, Fig. 9, has a dwell 56, with forwardly-projecting nose 57 for entering the recessed tail portion of a preceding link, and said intermediate link also has a rearwardly-projecting and recessed tail 59, similar to that of the foremost link. The rearmost group-link, Fig. 10, has a dwell 60, with forwardly-projecting nose 61 for entering the recess of the preceding link, and has a rear drop 62. By inserting between the foremost and the rearmost group-links more or less of the intermediate group-links a dwell of any desired duration in one position of the heddle can be effected, and any desired length of dwell in the other position of the heddle may be effected by the use in succession of more or less of the low links. Each of the high links has upon its high portion a side lug 63, which by contact with a laterally-adjoining link will serve to prevent lateral tilting of either link, and thus preserve the entire series of links in proper lateral position and prevent any strain upon either link due to lateral pressure thereupon.

Having thus described my invention, I claim and desire to secure by Letters Patent—

1. The combination, in a loom, of a series of heddles, a series of levers connected thereto, a series of pattern-chains acting directly upon said levers, a series of cam-disks on the pattern-chain shaft, laterally separated from said pattern-chains, a series of levers acted upon by said cam-disks, and connections between said cam-actuated levers and certain of the heddles which are in different planes from those of the levers, substantially as specified. 95

2. The combination, in a loom, of a series of heddles, levers connected thereto, a series of pattern-chains acting directly upon said levers, a series of cam-disks on the pattern-chain shaft, a series of levers acted on by said disks, and connections between said levers and certain of the heddles, elements of said connections being rock-shafts, each having two arms, one connected to the lever and the other laterally separated from the first and having connection with the heddle, substantially as specified. 105

3. The combination, in a loom, of a series of heddles, a series of levers connected thereto and having notches at their outer ends, pattern-chains acting upon said levers, and swinging fingers, one for each lever, said fingers being adapted to engage with the notched portions of the levers to hold them out of operative position, substantially as specified. 110

In testimony whereof I have signed my name to this specification in the presence of two subscribing witnesses.

ANDREW WEIMAR.
